UNITED STATES PATENT OFFICE.

IRA L. HYDE, OF CLAREMONT, VIRGINIA.

BOOK-SUPPORT.

SPECIFICATION forming part of Letters Patent No. 314,181, dated March 17, 1885.

Application filed June 17, 1884. (No model.)

To all whom it may concern:

Be it known that I, IRA L. HYDE, a citizen of the United States, residing at Claremont, in the county of Surry and State of Virginia, 5 have invented certain new and useful Improvements in Book-Supports, of which the following is a specification, reference being had therein to the accompanying drawings.

This invention relates to certain improvements in detachable and adjustable reading and writing tables for chairs and other articles of furniture; and it consists in the novel construction and arrangement of the parts, as more fully hereinafter described, and specifically pointed out in the claim.

In the accompanying drawings, Figure 1 represents a perspective view of my invention. Fig. 2 represents detached perspective views of a portion thereof. Fig. 3 represents a vertical sectional view of the desk and connections; and Fig. 4 a detailed view of the adjusting devices.

The letter A indicates the desk proper, which consists of a flat board or tablet, curved out 25 at one side, so as to fit against the body of the occupant of the chair and form a rest for the arm. The said board at convenient intervals is provided with a series of apertures, B, for the reception of the pins of an adjustable book-rest, C; which is employed when the table is used in an inclined position. The board or table near the upper end is provided with an elastic cord, D, which may be placed over the upper margin of the book to hold it open 35 and keep the leaves in place. Beneath the board is a drawer for ink, pencils, stationery, and other articles. To the under side of the board is secured a metallic quadrant or bracket, E, which has a curved slot, F, and an open slot, G, near its upper end. The said quadrant or bracket is provided with a lug or stud, H, which forms the center of a circle of which the curved slot is an arc.

The letter I indicates an upright or stand- 45 ard, which is flattened at its upper end, and

is formed with a half-circular bearing which engages the lug or projection in such manner as to let the table swing freely. The said standard is provided with a binding-screw, K, which sets through the curved slot and serves to bind 50 the parts together to hold the table in an adjusted position.

The letter L indicates a hollow standard, which has a jaw, M, at its lower end, which may be fitted over the arm of a chair, and M' a set-screw, by means of which it may be clamped in place. The said standard near its upper end is formed with a slot, N, on one side and with an aperture, P, directly opposite for the reception of a collar, P', having a 60 longitudinally-screw-threaded shank, R, upon which is a binding-nut, S. The standard I passes down through this collar and by it is adjusted at any desired elevation, as by loosening the nut the standard may be moved vertically, and by tightening it the standard is firmly clamped.

It will be seen that by the construction of the slotted quadrant the desk or table can be readily placed upon or removed from the 70 standard without removing the set-screw, which is a great convenience and prevents the loss of the set-screw.

Having thus described my invention, what I claim, and desire to secure by Letters Patent, is—

The combination, with the board or tablet A, provided with the quadrant E, having curved slot F, an intersecting radial slot, G, and a lug or stud, H, of the standard having 80 its upper flattened portion provided with a semicircular bearing to fit the stud H, and a binding-screw, K, the whole constructed and arranged substantially as shown and described.

In testimony whereof I affix my signature in 85 presence of two witnesses.

IRA L. HYDE.
